ELECTRIC FUSE

Arthur J. Lowe, West Kilbride, and Alexander Muirhead Ure Caldwell, Renfrew, Scotland, assignors to Imperial Chemical Industries Limited, a corporation of Great Britain

Application March 25, 1949, Serial No. 83,504
In Great Britain April 30, 1948

2 Claims. (Cl. 102—28)

1

The present invention relates to improvements in electric blasting fuses of the kind especially adapted for shot-firing in a blasting cartridge wherein a gas that does not support combustion is confined under pressure along with a combustible gas-producing heating charge within a pressure resisting container by a sealing device adapted to yield when a predetermined pressure has been built up.

In the "Cardox" (registered trade-mark) blasting system which is often employed in fiery or dusty mines, there is employed a pressure-resistant container leading to a vented discharge head with an interposed seal adapted to yield when a predetermined pressure has been built up by the gases produced by the charge in the container, which consists essentially of an ignitable heater charge comprising a mixture of an oxidising agent and one or more organic combustibles, and a charge of carbon dioxide liquefied by loading it under pressure. On ignition of the heater charge, pressure is built up very rapidly under the confinement until the seal yields, whereupon the partly gaseous products of the reaction stream through the discharge head and produce a blasting effect in the borehole. Owing to the quenching effect of the carbon dioxide on the gases from the heater charge, the products emerging from the discharge head do not ignite fiery or dusty atmospheres. The heater charge usually comprises a compact mixture of an inorganic perchlorate and an organic fuel which when ignited in the absence of the liquid carbon dioxide undergoes a strongly exothermic reaction with the production of flame.

It has been proposed in British specification No. 480,330 to provide a blasting cartridge of the kind described containing carbon dioxide or equivalent gas under pressure wherein there is employed a gas-producing charge having a self-combustible mixture comprising an oxidiser and a fuel in admixture with a non-combustible constituent (which upon combustion of the charge is capable of yielding gaseous products) in a proportion sufficient to render the charge not self-burning except when confined in the presence of the gas. This minimises the fire risks associated with the manufacturer handling and storage of the heater. It has also been proposed in British specification No. 560,227 to provide a composition for igniting heating or combustible gas-producing charges employed in blasting cartridges in which the blasting medium is a non-combustible gas such as carbon dioxide confined under pressure, and wherein on ignition of the gas producing charge combustion takes place so that

2

heat evolved causes the internal pressure to rise to a point when the cartridge is disrupted or a sealing device is ruptured and the non-combustible gas is suddenly released, this igniting composition consisting of a mixture of an oxidiser and sodium or potassium salicylate, which may if desired contain an endothermic salt in a proportion that renders the composition non self-burning in air but capable of initiating combustion of the gas-producing charge when under pressure in a cartridge. In accordance with one form of the invention described in this proposal a matchhead for igniting combustible gas-producing charges of the kind described comprises an electrical resistance wire embedded in a consolidated mixture of 68% potassium perchlorate, 17% sodium or potassium salicylate and 15% ammonium oxalate.

Experimental trials with electric blasting fuses having fuse-head compositions of the aforementioned kind and two differing resistance bridgewires of the same metal composition and of linear resistance 1400 ohms per metre and 3500 ohms per metre respectively showed an apparently anomalous behaviour, namely that although both types of fusehead operated the Cardox assembly satisfactorily, having firing currents of 0.50 amp. and 0.30 amp. respectively, nevertheless when tested at atmospheric pressures at a current sufficient to fuse the bridgewires, the fuseheads made with the higher linear resistance wire did not fire in any instance, whereas a large proportion of the fuseheads made with the lower linear resistance wire fired. This led to the belief that

35 whereas the minimum firing current under pressure bore the normal relationship to the linear resistance of the bridgewire, the performance of a fusehead in the atmospheric firing test was related to the total quantity of energy supplied by the bridgewire up to and including the moment of fusion. Therefore it was seen that as the diameter of the bridgewire was increased, ignition at atmospheric pressure would become more frequent.

45 The object of the present invention is to provide an electric blasting fuse adapted to ignite a heating charge or combustible gas-producing mixture confined under the pressure under which the carbon dioxide or equivalent gas is loaded 50 in a blasting cartridge as aforesaid but which will not fire under atmospheric pressure conditions when an electric current is passed through its resistance bridgewire, and wherein the combustible composition will be free from the corrosive effects associated with the presence of ammonium salts on base metal parts, and es-

specially brass or other copper metal parts, of the structure in contact with which it is consolidated, whereby its adhesion thereto on long storage is rendered safe.

According to the present invention an electric blasting fuse of the kind especially adapted for shot-firing in a blasting cartridge wherein a gas that does not support combustion is confined under pressure along with a combustible gas-producing heating charge within a pressure resisting container by a sealing device adapted to yield when a predetermined pressure has been built up comprised a resistance bridge wire of not more than about 1 millimetre length and not more than 0.025 millimetre thickness and preferably having a specific resistance of at least 100 micro-ohms wholly embedded in an ignitable composition consisting essentially of a mixture of potassium perchlorate and dinitroso-penta-methylene-tetramine.

It is to be understood that the lower limits of length and thickness of said resistance bridge wire are controlled by those practical constructional considerations well-known in the art of electric blasting fuse manufacture.

Dinitroso-pentamethylene-tetramine, as is known, may be prepared by a reaction between hexamethylene tetramine and nitrous acid in presence of aqueous nitric acid.

As the compositions employed in the construction of the electric blasting fuses according to the invention are capable of ignition under atmospheric pressure conditions when they are sufficiently strongly heated, the heat energy that it is permissible to develop in the resistance bridge wire by the passage of an electric current from the exploder, even if the current used is sufficient to fuse it, is limited. For this reason it is essential that the resistance wire should not have a diameter exceeding 0.025 millimetre or a length exceeding about 1 millimetre.

An alloy based on nickel and chromium may be used for the resistance bridge-wire.

While the proportion of potassium perchlorate and dinitroso-pentamethylene-tetramine theoretically required to give an equation in which the gaseous oxidation products are carbon dioxide, water and nitrogen is approximately 3:1, a considerable increase of either ingredient can be tolerated. The fusehead of the electric blasting fuse may conveniently be of the kind in which the pole pieces to which ends of the resistance bridge wire are attached are made of brass foil cemented to an insulating layer, but other forms of construction may be employed e. g. the resistance bridge wire may be attached to the air spaced ends of tinned copper wires kept in parallel relation by means of a plug of insulating material. The composition is conveniently applied in the form of a dope made up with a solution of nitrocellulose or other cement in a volatile solvent from which a bead is built up in known manner. Under atmospheric pressure conditions the resulting electric blasting fuses will not become ignited if an electric current is passed through the resistance bridge wire, e. g. as a result of stray currents, which minimises the hazards of manufacture, handling and storage, but under the high pressure at which the cartridge is charged e. g. 55 atmospheres and over even in the presence of liquid carbon dioxide it becomes ignited and effectively ignites heating charges or combustible gas-producing mixtures such as are used in "Cardox" blasting

e. g. those made in accordance with British specification No. 480,330.

The invention is further illustrated in the diagrammatic drawing accompanying the specification, which represents a vertical axial section of electric blasting fuse in accordance with the invention.

In the diagrammatic drawing 1 is a press-board sheet, 2 and 2¹ are brass foils cemented to the press-board sheet 1, the foil 2 and a portion of the thickness of the press-board sheet 1 being cut away at 3 to provide a step bridged by the resistance wire 4 which is soldered to the foils 2 and 2¹ at 5 and 5¹. 6 is a bead of a composition built up by drying of successive coats of a paste of a mixture of potassium perchlorate and dinitroso-pentamethylene-tetramine in the proportions 3:1 by weight in a 5% solution of nitrocellulose in an amyl acetate/amyl alcohol mixture, and subsequently drying of two coats of collodion 11 for waterproofing purposes. 7 and 7¹ are insulated leading wires of which the bared ends are soldered to the foils 2 and 2¹ at 8 and 8¹. 9 is a paper tube and 10 is a cast sulphur filling from which the bead protrudes, when a current sufficient to fuse the resistance wire 4 is applied through the leading wires 7 and 7¹ while the fuse is exposed at atmospheric pressure, the bead 6 fails to ignite, but in a Cardox blasting apparatus in contact with a gas-producing mixture as described in British specification No. 480,330 and charged with carbon dioxide at a pressure of 55 atmospheres the passage of a current even below that recognised to fuse the resistance wire 4 causes the bead 6 to ignite, and this in turn ignites the gas-producing charge.

After 3 months hot moist storage the fuses still function reliably and the bead 6 shows no signs of disintegration or failure to adhere to the brass foils.

We claim:

1. An electric blasting fuse of the kind especially adapted for shot-firing in a blasting cartridge wherein a gas that does not support combustion is confined under pressure along with a combustible gas-producing heating charge within a pressure resisting container by a sealing device adapted to yield when a predetermined pressure has been built up, said fuse comprising a resistance bridge wire of not more than about 1 millimetre length and not more than 0.025 millimetre thickness wholly embedded in an ignitable composition consisting of a mixture of potassium perchlorate and dinitroso-pentamethylene-tetramine.

2. An electric blasting fuse as claimed in claim 1 wherein the resistance bridge wire has a specific resistance of at least 100 micro-ohms.
